UNITED STATES PATENT OFFICE

141,254

DESIGN FOR AN ELECTROPLATING DEVICE

Gerald F. Cavanagh, Shaker Heights, Ohio, assignor to Jack & Heintz, Inc., Bedford, Ohio, a corporation of Ohio

Application January 22, 1945, Serial No. 117,552

Term of patent 14 years

(Cl. D26—1)

To all whom it may concern:

Be it known that I, Gerald F. Cavanagh, a citizen of the United States, residing at Shaker Heights, in the county of Cuyahoga and State of Ohio, have invented a new, original, and ornamental Design for Electroplating Device, of which the following is a specification, reference being had to the accompanying drawings, forming part thereof, wherein:

Figure 1 is a side elevational view of an electroplating device showing my new design,

Figure 2 is a top plan view of the device, and
Figure 3 is an end elevational view.

I claim:

The ornamental design for an electroplating device, substantially as shown.

GERALD F. CAVANAGH.
